UNITED STATES PATENT OFFICE.

COSIMO P. MORETTI AND EGISTO MEZZERA, OF LEAVENWORTH, KANSAS.

BELT.

Application filed December 6, 1926. Serial No. 152,904.

Our invention relates to military and other belts having buckles and other metal fittings, and our object is to provide said belts with novel fastening means which will 5 enable said buckles and fittings to be quickly removed for the purpose of being polished.

In order that the invention may be fully understood, reference will now be made to 10 the accompanying drawing, in which:

Fig. 1 shows a belt and a shoulder strap of the Sam Browne type equipped with our fastening devices.

Fig. 2 is an enlarged fragmentary detail 15 of one end of the belt with the buckle removed preparatory to being polished.

Fig. 3 is a fragmentary longitudinal section of the end of the belt disclosed by Fig. 2.

Fig. 4 is a detail side elevation of a 20 removable metallic button employed in carrying out the invention.

Referring in detail to the different parts, 1 designates the belt which is provided near 25 one end with slots or openings 2 for the passage of the tongues 3 of a removable metallic buckle 4. The belt 1 is provided at its inner side and at opposite sides of the openings 2 with fastening means comprising 30 socket members 5 and studs 6 which latter are adapted to be forced into the former for securing the end of the belt 1 in folded position over the pivotal bar 8 of the buckle 4.

The folded portion of the belt 1 is further 35 secured by a snap fastener consisting of a stud 10 and a socket 12 which latter is adapted to receive the former. The stud 10 projects outwardly or in an opposite direction from the studs 6, while the socket member 40 12 is carried by a broad flap 14 which is 45 stitched or otherwise secured at one end to the belt 1.

16 designates a removable metallic button which projects outwardly through the belt 45 1 in the same direction as the stud 10. A leather or other suitable washer 18 is interposed between the belt 1 and the inner end of said button 16 to prevent the latter from pulling outwardly through said belt. The 50 button 16 is adapted to pass through any of the button holes 20 in the opposite end of the belt 1 and coat with the buckle 4 in securing said belt in position around the waist. The flap 14 in addition to carrying the 55 socket member 12, acts as a pad in present-

ing a smooth surface to the body of the wearer and prevents the buckle 4, the studs 6 and the button 16 from pressing inwardly against the abdomen.

22 designates the shoulder strap, the forward end of which is adjustably connected to a short strap 24 through the intermediary of a metallic buckle 26, which latter is removably secured to the upper end of said strap 24. The lower end of the strap 24 is connected by a removable metallic button 28 to a short section of leather 30 which is looped through a metallic ring 32 removably connected to the belt 1 by a leather loop 34. One end of the loop 34 is stitched or otherwise permanently secured to the belt 1 and its free end is provided with a socket member 36 adapted to receive a stud 37, secured to the inner portion of said belt 1.

The rear end of the shoulder strap 22 is 75 removably connected by a metallic button 28^a, similar to the button 28, to a short strap 38 which is looped through a ring 40. The ring 40 is similar to the ring 32, and like the latter is removably connected to the 80 belt by a loop 42 having one end permanently fastened to the belt 1 and its opposite end detachably connected to said belt by a stud 36^a which engages a socket member fixed to the belt and similar in construction to the 85 socket members 5 and 12.

From the foregoing description it is apparent that the buckles 4 and 26, the buttons 16, 28 and 28^a, and the rings 32 and 40 can be readily removed for the purpose 90 of being polished, the polishing operation being accomplished much more readily after removal of the buckles, the buttons and the rings as stated, than if they were permitted to remain in position upon the belt 95 and the respective straps. Removal of the buckles, buttons and rings also prevents soiling of the belt and the straps with the polishing material.

While we have shown and described the 100 preferred form of our invention we reserve the right to such other forms and modifications as properly fall within the spirit and scope of the invention as claimed.

Having thus described our invention, what 105 we claim and desire to secure by Letters Patent, is:

In combination, a belt adapted to be folded at one end over a portion of a buckle and having an opening for the passage of the 110

tongue of said buckle, separable coengaging fastening means secured to said belt at opposite sides of said opening and adapted to detachably secure the end of the belt in folded position, a flap secured to the belt near the end above-mentioned and adapted to cover the adjacent portions of said fastening means and the buckle, a socket se-

cured to the free end of said flap, and a stud on the belt adapted to detachably engage the last-mentioned socket.

In testimony whereof we affix our signatures.

COSIMO P. MORETTI.
EGISTO MEZZERA.
